UNITED STATES PATENT OFFICE

2,518,557

FRAME AND FASTENING MEANS THEREFOR

Walter M. Krantz, Youngstown, Ohio, assignor, by direct and mesne assignments, to Ace Storm Window Company, Youngstown, Ohio, a corporation of Ohio

Application August 7, 1945, Serial No. 609,456

1 Claim. (Cl. 189—76)

This invention relates to a frame structure formed of cut sections of strip stock and to a fastener for affixing the frame so formed to a window opening.

The principal object of the invention is the provision of a fastener for attaching a storm sash frame to a window casing.

A further object of the invention is the provision of means for adjustably fastening a storm sash frame to a window opening.

A still further object of the invention is the provision of a fastener bracket for use with a storm sash frame providing for the optional location of the bracket at any place along the said frame.

The frame and means for fastening the same to a window opening shown and described herein has been devised to provide a simple and economic method of mounting a metallic frame on a window opening such as, for example, a storm sash frame on a dwelling house window opening. It is well known in the art that many and various storm sash constructions are commonly employed for the purpose of insulating window openings in various dwellings, buildings, etc., and that several methods of mounting the storm sash frames on the exterior of the window openings have been devised and are commonly employed. First among these methods is the simple provision of a plurality of screws engaging openings formed in an overlying flange of the storm sash frame, the said screws directly engaging the window casing of the window opening in the dwelling or other building. The present invention relates to a method of mounting a storm sash frame by affixing it to the interior structure of the window casing rather than the exterior exposed portions thereof, and at the same time provides a degree of adjustment heretofore believed impossible in the mounting of such storm sash.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a cross sectional side elevation of a section of storm sash frame and fastening means therefor.

Figure 2 is a complete view of a section of storm

1 sash frame as illustrated in Figure 1 and illustrates the use of a pair of fastening means on a section of sash frame. Line 2—2 on Figure 1 indicates the elevation of Figure 2.

2 Figure 3 is a perspective elevation of the fastening means employed in the device illustrated in Figures 1 and 2.

3 By referring to the drawings and Figures 1 and 2 in particular, it will be seen that a section of 10 storm sash frame 10 has been disclosed which consists of a metallic shape preferably of extruded form having a central body area and a pair of oppositely disposed flanges 11 which, together with the body section, form a surface flange 12. In 15 use, the surface flange 12 is the front or finished portion of the storm sash frame. The metallic shape 10 is also provided with a centrally located upstanding rib 13, the uppermost section of which is T-headed by reason of the provision of a pair 20 of outwardly and downwardly formed parallel flanges 14. Adjacent each side of the upstanding rib 13 there are a pair of axially extending parallel grooves 15 which match, in opposed relation, the lower surfaces of the outwardly and 25 downwardly extending flanges 14 forming the T-headed portion of the upstanding rib 13 of the metal shape 10. It will thus be observed that the metal shape consists of a surface flange 12 ribbed on the back thereof and the rib provided 30 with a pair of oppositely disposed dovetailed channels. Sections of the metal shape 10, when cut and mitered at their corners and joined by appropriate corner constructions, form an efficient storm sash frame of strong and durable construction. In order that this frame may be 35 conveniently and inexpensively mounted in a window opening such as in a dwelling house, a fastener has been provided which is illustrated in cross sectional detail in Figure 1 and in side elevation in Figure 2 and in perspective elevation in 40 Figure 3. The fastener means, as may be seen by referring to these figures of the drawings, consists of a small bracket 16 having a dovetailed extension 17 formed axially thereof and of a size 45 enabling it to slide within one of the dovetailed channels formed on the sides of the upstanding rib 13 of the metal shape 10. In forming a storm sash frame utilizing the fastener 16, pairs of the fastener 16 are slidably engaged with the outermost channel of the metal shape 10 prior to the formation of the actual frame so that at such time as the frame is formed they are available for utilization in fastening the frame to a window casing. It is obvious that in this position they

55 are slidable along the complete length of the sec-

tion of metal shape 19 thereby being capable of location in any desired spot therealong. The fastener 16 is formed with an offset axially extending flange 18 which in turn is provided with a vertically positioned slot 19 which is adapted to receive a screw 20. It will be observed that the positioning of the slot 19 at right angles to the main body portion of the fastener 16 permits variance of the screw location inwardly or outwardly of the window opening such as represented by broken lines in Figures 1 and 2 and indicated by the numeral 21. It will thus be seen that a simple and efficient fastening means for mounting a storm sash frame on a window of a dwelling house or building, which fastening means consists of a simple bracket capable of being affixed in a slideable manner to the storm sash frame and providing means for mounting a screw through the said bracket so as to engage a portion of the window casing of the window opening. The bracket is of simple, inexpensive construction and may therefore be obviously produced at small cost and hence widely distributed. It will also be observed that by utilizing the bracket, the fastening means for a storm sash frame as disclosed herein, the exposure of fastening means commonly engaging the surface flange of the said frame is entirely eliminated both to the structural advantage of the sash frame itself and the improvement of the appearance of the frame as well.

Having thus described my invention, what I claim is:

The combination of a channeled storm sash frame and a mounting bracket therefor, the said channeled storm sash frame including an upstanding axially extending rib having a dovetailed channel formed in at least one side thereof, the said fastening means comprising a bracket having a dovetailed section formed thereon at right angles thereto for engaging the said dovetailed channel, and a slot formed in the bracket for the reception of a screw to facilitate the attachment of the said fastening means to a window casing so as to hold the said frame in position thereon.

WALTER M. KRANTZ.
